CLAIM

I claim the ornamental design for a pet toy, as shown and described.

DESCRIPTION

FIG. 1 is a top, perspective view of a pet toy of the present invention;

FIG. 2 is a front elevation view of the toy of FIG. 1;

FIG. 3 is a back elevation view of the toy of FIG. 1;

FIG. 4 is an elevation view of the right side of the toy of FIG. 1;

FIG. 5 is an elevation view of the left side of the toy FIG. 1;

FIG. 6 is a top plan view of the toy of FIG. 1;

FIG. 7 is a bottom plan view of the toy FIG. 1;

FIG. 8 is a sectional view taken on line 8—8 on FIG. 2, showing two tethers dangling from the ball top and several tethers on the ball bottom; and,

FIG. 9 is a sectional view taken on line 8—8 on FIG. 2, showing several tethers dangling from the ball top and several tethers on the ball bottom.

The broken lines are for purposes of illustration only and form no part of the claimed design.
